CLOSURE FASTENER

John R. Burbridge, Kenosha, Wis.

Application June 22, 1934, Serial No. 731,827

2 Claims. (Cl. 292—261)

This invention appertains to closure fasteners, and more particularly to a novel device for holding the sliding sashes of a window in a closed position or any preferred, adjusted open position.

5 I am aware of the fact that it has been proposed to provide concentric discs, cams, and the like for window sash fasteners, but all of these devices (with which I am familiar) are open to serious objections. Some fail to positively hold the sashes against unauthorized movement; others tend to seriously mar the rails of the sashes; and others are hard to release after having finally caught the sash rails.

10 It is, therefore, one of the salient objects of my invention to provide a sash fastener, which will be positively urged into tight locking position with the sashes, for forcing the sashes apart and into tight binding contact with the sash stops, or guides, when unauthorized attempt is made to open the window from the outside, and thus effectively hold the sashes closed against such attempts, and which can be quickly released by persons on the inside of the window, the device being so constructed that the marring of the 15 sashes is eliminated.

20 Another salient object of my invention is to provide a sash fastener embodying rotatable friction rollers carried by a manipulating lever pivoted on a bracket secured to one sash, novel means being provided for positively forcing the rollers into tight binding contact with the other window sash and against rotation when forcible means is used to open the window.

25 A further object of my invention is the provision of pinions carried by the friction rollers for meshing engagement with inclined rack bars on the bracket, the pinions and rack bars functioning to urge the rollers into locking position and against rotation when the sashes are moved in one direction (to an open position) and to a released position when the sashes are moved in an opposite direction.

30 A further object of my invention is to provide novel means for constructing the bracket and for associating the bracket with the window, so as to prevent the operation of the lever and rollers by the insertion of instruments between the meeting rails of the sashes.

35 A still further object of my invention is to provide a sash fastener of the above character, which will be durable and efficient in use, one that will be simple and easy to manufacture, and one which can be placed upon the market at a reasonable cost.

40 With these and other objects in view, the invention consists in the novel construction, arrangement and formation of parts, as will be herein-after more specifically described, claimed and illustrated in the accompanying drawing, in 45 which drawing:—

Figure 1 is a fragmentary longitudinal section through a pair of window sashes, showing my novel fastener incorporated therewith, the fastener being shown in its operative position.

Figure 2 is a top plan view of the fastener removed from the window.

Figure 3 is a longitudinal section through the fastener, taken substantially on the line 3—3 of Figure 2.

Figure 4 is a transverse section through the fastener, taken substantially on the line 4—4 of Figure 3, looking in the direction of the arrows.

Figure 5 is a side elevation of a slightly modified form of fastener.

Figure 6 is a top plan view of the same.

Figure 7 is a longitudinal section through the modified form of fastener, taken on the line 7—7 of Figure 6.

Figure 8 is a transverse section through the modified form of fastener, taken on the line 8—8 of Figure 7, looking in the direction of the arrows.

Referring to the drawing in detail, wherein similar reference characters designate corresponding parts throughout the several views, the letter F generally indicates my improved fastener, and W a window with which the same can be associated.

The window W includes top and bottom sliding sashes 10 and 11. These sashes are of any preferred construction, and the upper sash 10 includes side rails 12 and a bottom, or midrail, 13. The lower sash 11 includes side rails 14 and a top, or midrail, 15. As in the ordinary construction, the midrails 13 and 15 are adapted to abut when the sashes are in their completely closed positions.

My improved fastener F includes a bracket 16 for rockably supporting the manipulating lever 25, which in turn carries the pair of friction rollers 26. The bracket 16 includes a base plate 17 having the upstanding, spaced, parallel side walls 18. These side walls 18 extend to the extreme front of the base plate 17 to provide guards 19, for a purpose which will be later set forth.

In rear of the guards 19, the inner edges of the side walls 18 are provided with rack bars 20. These rack bars are at an angle to the vertical and extend upwardly and rearwardly. The purpose of these rack bars 20 will be hereinafter more fully set forth.

Extending transversely across the bracket is a pivot pin 21, and the terminals of the pivot pin are supported by the side walls 18 at a point intermediate the ends thereof. The base plate 17 can be provided with openings 22 for the reception of fastening elements (not shown) to permit the firm securing of the bracket to the top, or midrail, 15 of the lower sash 11.

By referring to Figure 1 of the drawing, it will be noted that the bracket extends beyond the

inner edge of the midrail 15 for engagement with the upper surface of the midrail 13. The purpose of this will also be later described.

The manipulating lever 25 has its side edges 5 provided with depending pivot ears 21. These ears 21 are located intermediate the ends of the lever, and are provided with enlarged bearing openings 28 for loosely receiving the pivot pin 21. The inner end of the lever 25 is rolled to 10 provide a hinge barrel 29 for reception of the pintle 30. This pintle 30 has mounted thereon the friction rollers 26, and the rollers include metallic hubs 31 and rubber or felt tires 32. Formed on the hubs 31 of the rollers 26 are pinions 32, which mesh with the rack bars 20. The 15 outer end of the lever has formed thereon a manipulating handle 33.

The bracket is applied to the midrail 15 of the lower sash 11 adjacent to one side thereof, 20 so that the rollers 26 will be enabled to frictionally engage the inner face of the side rails 12 of the upper sash 10.

In use of the fastener, considering that the 25 sashes are in their closed position (see Figure 1 of the drawing) and an attempt is made to open either the top or bottom sash, the rollers will be swung downwardly and the pinions 32, riding on the rack bars, will force the rollers into tight engagement with the rails 12. This will 30 force the sashes apart and cause the same to bind against the stops, or guides. Obviously, the more pressure is exerted on the sashes, the further apart the sashes will be forced. Accidental rotation of the rollers is prevented, due to the 35 engagement of the pinions with the rack bars. Thus, the sashes will be firmly held in a closed position.

I lay particular stress on the pinions and rack bars, in that were the rollers left for free rotation, opening movement of the sashes might be 40 had when undue pressure is placed on the sashes, as the rollers would then tend to rotate with the longitudinal movement of the sashes.

When the sashes are moved to a closed position, the rollers will tend to move upwardly and 45 away from the rails 12, thus allowing free closing movement of the sashes. When the sashes are locked and it is desired to release the same, it is merely necessary to raise the sashes, and the pinions 32 riding on the inclined rack bars 20 will force the rollers away from the rails 12. Obviously, the sashes can be locked in a partially 50 opened position, when such is desired. The handle 33 forms a convenient means for raising the rollers when the sashes are being opened 55 from the inside of the window.

By having the base plate 17 extending over the midrail 13, persons are prevented from inserting implements between the midrails 13 and 60 15 and pushing up on the rollers. The side guards 19 also help to prevent the insertion of instruments over the base plate 17 and into engagement with the rollers. Thus, the sashes will be securely held against unauthorized opening 65 movement even though there should be play between the meeting faces of the rails 13 and 15.

In Figures 5 to 8 inclusive, I have illustrated a slightly modified form of the fastener. This fastener operates exactly in the same manner 70 as the form previously described, and the differ-

ence between the two is mainly in the construction of the bracket.

The modified form of the device is generally indicated by the reference character M, and the same includes the supporting and attaching bracket 35 which can be stamped from sheet metal, if so desired. This bracket 35 includes longitudinally extending, like side plates 36 connected by an inverted U-shaped bridge piece 37. The inner edges of the bridge piece has formed 10 thereon rack bars 38 which are arranged at an angle to the vertical.

Disposed between the side walls of the bridge piece 37 is the manipulating lever 39, and this lever is provided intermediate its ends with an 15 enlarged opening for receiving the pivot pin 39' anchored to the connecting piece.

The forward end of the lever carries a pintle, or shaft, 40 on which is secured the friction wheels 41. These friction wheels 41 have secured thereto pinions 42 which mesh with the 20 rack bars 38. The outer end of the lever 39 is provided with the manipulating finger-piece, or handle, 43.

Formed on the outer side edges of the plates 25 36 are upstanding guard flanges 44, and the inner edges of the plates 36, at their forward ends, are provided with abutting guard lips 45.

As brought out above, the modified form of fastener M operates and functions in the same 30 manner as the form first described. It is to be noted, however, that the lips 45 form means for preventing the insertion of an instrument up between the plates 36 to lift the rollers, and the guard flanges 44 also prevent the insertion of an 35 instrument around the base plates.

As shown in dotted lines in Figure 1 of the drawing, a housing, or guard, can be provided for the device, and, if preferred, the same can be slipped over the base plate and held in place 40 by frictional contact with the base plate.

Changes in details may be made without departing from the spirit or the scope of this invention, but what I claim as new is:—

1. A sash fastener comprising, a bracket 45 including a pair of longitudinally extending attaching plates, an inverted U-shaped connecting piece uniting the plates, rack bars formed on the inner edges of the connecting piece disposed at an angle to the vertical, a lever loosely and rockably supported by the connecting piece, friction rollers rotatably carried by the forward end of the lever, pinions rotatable with the rollers meshing with the rack bars, upstanding guard flanges on the side edges of the plates, and inwardly directed abutting lips formed on the inner edges of the plates at the forward ends thereof.

2. A sash fastener comprising a bracket 60 including an attaching portion and a pair of upstanding, spaced, parallel side plates having inclined rack bars formed on their forward edges, a cross-pin carried by said side plates, a lever loosely and rockably mounted upon the pin, a bearing on the lever, a shaft in the bearing, and a pair of rollers rotatably mounted on the shaft, each of said rollers including a hub having an integral pinion engaging a rack bar, and a compressible tire on the hub at one side of the pinion.

JOHN R. BURBRIDGE. 70
